CLAIM

The ornamental design for a display screen with a graphical user interface, as shown and described.

DESCRIPTION

FIG. 1 is a front view of a display screen with a graphical user interface;

FIG. 2 is a front view of a display screen with a graphical user interface;

FIG. 3 is a front view of a display screen with a graphical user interface;

FIG. 4 is a front view of a display screen with a graphical user interface;

FIG. 5 is a front view of a display screen with a graphical user interface;

FIG. 6 is a front view of a display screen with a graphical user interface;

FIG. 7 is a front view of a display screen with a graphical user interface;

FIG. 8 is a front view of a display screen with a graphical user interface; and,

FIG. 9 is a front view of a display screen with a graphical user interface.

In the drawings, each indicator bar provides a variable level of a respective parameter. The drawings include one or more of the display screen or portion thereof, a menu, graphs, text, symbols, and mineral extraction equipment, such as a blow-out preventer or diverter, as context. In the drawings, the solid lines illustrate the claimed ornamental design, whereas the broken lines illustrate environmental features that form no part of the claimed ornamental design.

1 Claim, 9 Drawing Sheets
